(57) **CLAIM**

The ornamental design for a rack and container set, as shown and described.

DESCRIPTION

FIG. 1 is a perspective view of a rack and container set showing my new design.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof.

FIG. 8 is a perspective view of the rack part of the rack and container set of FIG. 1 isolated for clarity.

FIG. 9 is a front view thereof.

FIG. 10 is a back view thereof.

FIG. 11 is a right side view thereof.

FIG. 12 is a left side view thereof.

FIG. 13 is a top view thereof.

FIG. 14 is a bottom view thereof.

FIG. 15 is a perspective view of one container part of the rack and container set of FIG. 1 isolated for clarity; all of the containers of the rack and container set are identical.

FIG. 16 is a front view thereof.

FIG. 17 is a back view thereof.

FIG. 18 is a right side view thereof.

FIG. 19 is a left side view thereof.

FIG. 20 is a top view thereof; and,

FIG. 21 is a bottom view of the container.

The oblique shade lines in FIGS. 1-5, 15-19, and 21 are included to convey that the surfaces are reflective. When a container is placed in the rack, an indentation on the bottom of the container fits into a corresponding protrusion on the rack.
